UNITED STATES PATENT OFFICE.

FRITZ WEINBERG, OF SANNIESHOE, TRANSVAAL, SOUTH AFRICA.

GARTER OR SOCK SUSPENDER.

Application filed April 26, 1921. Serial No. 464,506.

To all whom it may concern:

Be it known that I, FRITZ WEINBERG, a subject of the King of Great Britain, and resident of Sannieshof, Transvaal Province, 5 Union of South Africa, have invented certain new and useful Improvements in Garters or Sock Suspenders, of which the following is a specification.

This invention relates to garters or sock 10 suspenders, and in particular to that kind known as "pad garters."

Such garters as commonly manufactured consist of a pad—from which the clip or part which engages with the sock depends—and an extendible band—which encircles the leg—provided at its ends with a fastening device.

The bands of such garters are usually made from elastic webbing or similar 20 resilient material, the india-rubber component of which, as is well known, is of a highly perishable nature. This characteristic of the elastic material is intensified as the webbing band is ordinarily under tension 25 all the time the garter is in use.

Now the object of this invention is to produce a garter of the nature referred to in which rubber will be dispensed with, and to utilize means of a much more durable 30 nature in substitution therefor.

The improved garter gives all the advantages of those at present made with the further advantage of infinitely greater durability.

35 The invention will be described with the aid of the accompanying drawing, wherein—

Fig. 1 shews a part sectional view of a garter embodying one form of the invention,

40 Fig. 2 is a part sectional view of a portion of a garter illustrating a modification of the resilient tightening means for the band.

45 Fig. 3 is a view shewing a detail of construction of the casing of the resilient tightening means.

In Fig. 1 the numeral 1 denotes the pad of the garter which may be made of leather, 50 fabric or any other suitable flexible material. 2 is the clip or part which engages with the sock, and is shewn comprising the front loop 3 and back piece 4 carrying the button or projection 5 which engages in the 55 loop 3, and between which loop 3 and back piece 4 and button 5, the material of the

sock is placed and retained in the usual manner. The back piece 4 is suitably attached to the pad 1, and the loop 3 is loosely or hingedly connected to the pad 1 in front 60 of the back piece 4, in the ordinary or any other suitable manner.

6 is the band which encircles the leg, and is connected at one end 7 to the pad 1.

The band 6 is made of any suitable flexible material, such as a soft and strong leather, woven fabric, et cetera. The band 6 is shewn consisting of three parts or sections 8, 9, 10. Intermediate the inner ends of the sections 8, 9, a resilient device is 70 positioned, and in like manner a similar resilient device is placed between the inner ends of the sections 9, 10.

In Fig. 1 each of the resilient devices consists of three helical springs 11, which are 75 attached at their ends to preferably metal loops 12, which serve for connecting the springs to the inner ends of the sections of the band. The springs 11 are each enclosed by two telescopic casings or tubes 13, 14, 80 which may be made of leather or any other suitable material which is sufficiently rigid for the purpose. The outer ends of the two parts of the telescopic casing or housing may be suitably attached to the loops 12, or to the 85 ends of the springs 11. As the springs 11 expand or contract when the garter is brought into use the telescopic casings 13, 14 move outward and inward in a manner that will be understood.

90 Although I shew two of the spring devices in the band 6, it is to be understood that one only or more than two may be provided, and that each device may comprise any desired number of helical metal springs 95 enclosed in telescopic casings.

If desired the leather or like telescopic casings may be lined with thin metal tubes, in order to facilitate the telescopic movement.

100 In the modification shewn in Fig. 2, instead of separate telescopic casings being provided for each spring (as in Fig. 1) the whole three are enclosed in a single telescopic casing or housing, comprising the 105 two parts 15, 16 suitably flattened at two opposite sides.

110 As illustrated at 17, 18, in Fig. 3, the parts 15, 16, of the single casing may be provided with metal linings if preferred or found desirable.

The garter is fitted at the ends with the

ordinary hook 19 and loop 20, or other suitable fastening means and with the slide, buckle or shackle 21 for adjusting the length of the band as may be required.

5 When the garter is brought into use the springs and casings of the resilient devices admit the band to be extended to place the hook 19 in engagement with the loop 20, and, when the band is released, contract 10 sufficiently to shorten the band and maintain the garter in the desired position around the leg.

What I claim as my invention and desire to protect by Letters Patent is:—

15 1. A garter or sock suspender comprising a pad to which the sock is adapted to be detachably secured, a sectional band made of soft non-extendible material, which is adapted to encircle the leg, means for detachably connecting the ends of said band, means for adjusting the length of said band, and a plurality of resilient devices placed intermediate the sections of said band, each of said devices including a plurality of 20 helical metal springs, loops for attaching the 25

ends of said springs to the ends of the sections of the band, and a telescopic casing surrounding said springs, as set forth.

2. A garter or sock suspender comprising a pad to which the sock is adapted to be 30 detachably secured, a sectional band made of soft non-extendible material, which is adapted to encircle the leg, means for detachably connecting the ends of said band, means for adjusting the length of said band, and a plurality of resilient devices placed intermediate the sections of said band, each of said devices including a plurality of helical metal springs, loops for attaching the 35 ends of said springs to the ends of the sections of the band, and a telescopic casing surrounding said springs, said telescopic casing being lined with metal, as set forth.

In testimony whereof I have signed my name to this specification in the presence of two subscribing witnesses.

FRITZ WEINBERG.
